UNITED STATES PATENT OFFICE.

ISAAC GORDON, OF NEW YORK, N. Y.

WATER CYCLE.

Application filed June 23, 1925. Serial No. 39,132.

The invention relates to a water cycle which is adapted to be operated by either hand power, foot power, or both hand and foot power simultaneously.

- 5 One of the objects of the invention is to provide a device of this character which will enable any one to float upon water at a great rate of speed by using either hand or foot power alternately or hand and foot 10 power simultaneously, thereby enabling anyone to reach a certain point across or on waters regardless of whether they can swim or not.

Another object of the invention is to provide a safe device for passengers on steamships, in case of danger, to reach a certain point and thus save life.

Still another object of this invention is to enable an army to cross certain rivers at 20 any time during day or night without alarming the enemy and at a greater speed than by crossing temporary made bridges.

Further objects of this invention will be apparent from the following detailed description when taken in connection with the accompanying drawings in which:

Figure 1 is a side elevational view of the cycle detached from the body.

Figure 2 is a perspective view of two hollow pipes with hinges and straps attached.

Fig. 3 is a plan view of the rotating wheels and the two sides of the body containing all machinery shown in the drawing of Fig. 1.

Fig. 4 is a perspective view of the complete hydro cycle including all sections shown in Figs. 1, 2 and 3 and ready for action.

Referring to the drawing more in detail, numeral 1 indicates a long shaft carrying screw propeller 2 rotated by wheel 3 through foot power paddles 4. Wheel 3 revolves wheel 6 and bevel gear 7 through cog chain 5. Wheel 7 revolves a smaller bevel gear 9 on shaft 1. As each large wheel revolves a smaller one, the number of revolutions of bevel gear 9, attached to shaft 1, will be considerably greater than the number of revolutions of the wheel 3, thereby enabling the cycle to proceed at a great speed. Group 45 of wheels 10, 12, 13 and 14 are operated by hand power arms, 11, and in the same manner as, and so as to co-operate with, the group of wheels operated by foot power, excepting that it is being worked by cog 50 wheels instead of chain. In this manner,

a person can use foot power and hand power simultaneously or either one.

Fig. 2 indicates hollow tubes 15, side arms 16 and canvas straps 18. Tubes 15 which are hingedly connected at 17 can be brought together or opened apart on these hinges. These hollow tubes can be made of aluminum with buoyancy enough to float the entire machine with a human body on it as shown in Fig. 4. Cork padding or air spaces may 65 also be employed to float this device—the hydro cycle.

It may be noted here that the invention is not limited to the use of any particular type of propelling wheels, gear wheels, driving chains, floating matter or general style and size.

Fig. 3 is a top view of hand and foot power hydro cycle containing the entire group of wheels and shaft shown in Fig. 1, two wooden sides 22—22, canvas straps 21—21 and steering gear 23—23. The side boards 22 are about four inches wide and the proportional length for the different sizes and weights required by the user. These side 70 boards are held together by bolts or wooden pegs 24—24, spaced about four inches apart. The entire machine is adapted to be steered by steering gear 23 which operates the rudder 27.

Fig. 4 is the machine complete with the hollow tubes 15—15, side supports 16—16 attached to the entire body shown in Fig. 3. The front gear 10 can be put out of gear by raising and placing the axle of same in 90 half circle groove 25. This would stop the entire group of wheels in case the operator prefers to use foot power only.

Here again I do not wish to be limited to the shape of the side boards and general constructions of the machine. The same may be changed by raising the front part of the body above the rear end. Since the hollow tubes are foldable on hinges 17—17, the entire lower body 26—26 can be made in two 100 sections so as to enable the user to put it together or take it apart as conditions may require and for better carrying convenience.

In accordance with the patent statutes, I have described what I now believe to be the best embodiment of the invention, but I do not wish to be understood thereby as limiting myself or the scope of the invention, as many changes and modifications may be made without departing from the spirit of 110

the invention; all such I aim to include in the scope of the appended claim.

What I claim as new and desire to secure by Letters Patent is:

5 A water cycle including a body portion, a shaft rotatably mounted on said body portion, a propeller wheel on said shaft, two sets of gearing associated with said shaft, a hand-

crank for operating one set of gearing, a foot-crank for operating the other set of gearing, 10 said body portion provided with a semi-circular groove in which a part of said gearing is journalled and whereby the same may be shifted out of gear.

ISAAC GORDON.
